MANUFACTURE OF SOAP

Leopold Sender, Baltimore, Md., and Leo D. Jones,
Philadelphia, Pa., assignors to The Sharples
Corporation, Philadelphia, Pa., a corporation
of Delaware

Application November 25, 1943, Serial No. 511,708

3 Claims. (Cl. 260—418)

The present invention pertains to manufacture of soap by a continuous process. It is an improvement in the prior processes described in the patents to Scott 2,300,749 and 2,300,750. In the processes of the above-mentioned Scott patents, an aqueous saponifying reagent (e. g., lye) is passed continuously into confluence with a flowing stream of fat and the fat is saponified by mixing of the saponifying reagent therewith while maintaining the reagent mixture at an elevated temperature. From the mixing apparatus in which the saponification is accomplished, the resulting soap-containing mass is passed through a centrifugal separator which removes spent saponifying reagent from the formed soap, which has previously been grained by the addition of salt or equivalent reagent.

In practice of processes such as those described in the Scott patents, difficulty has sometimes been encountered due to formation of emulsions of soap in spent reagent which are extremely difficult to separate. As a result of this difficulty, it is necessary to provide centrifugal equipment of capacity in excess of that which would be required, if such difficulties were not encountered. The reason for necessity of such excess centrifugal capacity is that, in cases of centrifugal treatment of mixtures which are difficult to separate into soap and aqueous phases respectively, sufficient centrifugal capacity must be available to provide more prolonged centrifugation than would otherwise be necessary.

The present invention rests upon the discovery of an improved process by which the formation of difficultly separable emulsions may be consistently avoided. As a result, the processes of the Scott patents, when modified to include the features of the present invention, can be uniformly operated to obtain a saponification reaction mixture which can be readily separated centrifugally.

In the practical operation of a process such as that described in either of the Scott patents discussed above, mixing apparatus is used which provides for progressive passage of the reaction mixture through a series of mixing compartments. These mixing compartments may be either separate compartments of a single large mixer sub-divided by baffles, or they may be in the form of a plurality of separate small mixers. In either case, the purpose of compartmentation is to insure a more thorough reaction of the fat with the saponifying reagent to cause thorough utilization of the saponifying reagent, and to

obtain a higher degree of saponification of the fat than would otherwise be possible. A feature of the present invention lies in the fact that care is exercised to obtain saponification of the fatty acid content (both free and combined) of the fat under treatment to an extent providing a mixture in each of the respective compartments of the mixer, in which the available fatty acid has been saponified to an extent in excess of 85% or below 70%. As a further feature, a compartment of the mixer upstream from the furthest downstream compartment contains a mixture of which the fatty acid content of the available fat has been saponified to an extent in excess of 85%. As a still further feature, a compartment of the mixer downstream from the compartment in which the saponification has proceeded to an extent in excess of 85% is provided with a connection through which a further quantity of fat is fed thereto for saponification. This last-mentioned feature, when combined with the feature of saponification in excess of 85% in one of the earlier compartments of the mixer, renders it possible for the operator to obtain effective utilization of the aqueous saponifying reagent in spite of the fact that an excess of this reagent may previously have been added in order to insure saponification in excess of 85% in an upstream compartment of the mixer.

The above and other features of the invention will be more evident from a reading of the following specification in the light of the attached flow sheet, in which,

35 Figure 1 represents one embodiment of the invention, and

Figure 2 represents an alternative embodiment.

As illustrated in Figure 1, fat from container 10 is continuously passed into confluence with an aqueous saponifying reagent which may be lye from container 11, the fat and reagent solutions being pumped into confluence in mixer 14 by pumps 12 and 13, respectively, as described in the above-mentioned Scott patents. The fat may be pre-heated in heater 15 to bring it to a saponifying temperature before admixture with the lye. Brine may also be passed from container 22 by pump 23 into confluence with the fat and lye in mixer 14, in order to grain soap formed by the saponifying reaction. Alternatively, such brine may be mixed with the lye before being passed to the mixer 14, or brine may be passed to a subsequent compartment of the mixer 14 as discussed in the patent to Scott,

2,300,749. In this connection, it is pointed out that the present invention is not limited to any particular method or point of introduction of the brine solution, and that the soap formed by the reaction may be grained by the addition of brine, excess saponifying reagent or other electrolyte capable of effecting such graining, before being subjected to centrifugation, as in either of the above-mentioned Scott patents.

As illustrated in each of the figures of the drawing, the mixer comprises a plurality of mixing compartments. Figure 1 of the drawing illustrates the provision of four successive compartments, 16, 17, 18 and 19, of which the first or upstream compartment 16 is of substantially larger capacity than the subsequent or downstream compartments. Each compartment may also be provided with a coil 20 for passage of a heat exchange fluid. Thus, a heating fluid may be passed through the coil 20 in the compartment 16, in order to bring the reaction mixture to a very high temperature to insure reaction of the fatty acid content to an extent above 85% in this compartment, and the downstream compartments 17, 18 and 19 may have cooling fluids passed through the coils of these compartments in order to cool the reaction mixture to a temperature sufficiently low to permit centrifugation without vaporization of aqueous phase as it enters the centrifugal 21.

As pointed out above, the applicants have discovered that, by maintaining an extent of saponification of the fatty acid of the fat fed to the mixer 14 which is below 70% or above 85% in each mixing compartment, the operation of separation of the grained soap from the aqueous reagent solution may be greatly facilitated. The primary conditions affecting the extent of saponification of the available fatty acid are the amount and strength of the saponifying reagent, the degree of heat applied to effect saponification and the time interval provided for such saponification. The extent of saponification in a given compartment may be increased by an increase in the value of any one of these four factors. In the practice of the invention as illustrated in Figure 1, the compartment 16 is made larger than succeeding compartments and additional heat is also applied to the reaction mixture in this compartment, in order to insure attainment of saponification in excess of 85% in that compartment.

While, as noted above, a primary feature of the present invention consists in attainment of saponification in excess of 85% in some compartment of the mixer upstream from the furthest downstream compartment thereof, this result of extensive saponification in an upstream compartment, and particularly in the first compartment of the mixer, sometimes requires addition of a relatively high proportion of saponifying reagent to fat. As a consequence of this fact, it is sometimes difficult to attain the object of saponification in excess of 85% in an upstream compartment of the mixer consistently with attainment of the desirable depletion of the saponifying reagent. In accordance with the present invention, a further quantity of fat is separately introduced into a compartment of the mixer downstream from the first such compartment in which saponification to an extent in excess of 85% is attained, this additional quantity of fat serving to utilize excess saponifying reagent which may initially be introduced to in-

sure saponification in excess of 85% in a compartment in advance of that into which the additional stream of fat is introduced. By introducing a separate quantity of fat in this manner, the desirable depletion of the reagent is attained. In connection with this feature of introduction of further fat for depletion of reagent, one should, of course, avoid introducing a quantity of fat sufficiently large to produce, in 10 the compartment into which such additional fat is introduced, a mixture containing fat saponified to an extent less than 85%. In the practice of the invention as illustrated in Figure 1, these results are attained by introducing a part of the 15 fat from container 10 directly into the second compartment 17 of the mixer 14. Control of the fat introduced through the by-pass line 26 and that through the main line 27 may be accomplished by valves 24 and 25, respectively. By 20 controlling these valves, it is possible for the operator to control the relative proportions of fat introduced into the compartments 16 and 17, respectively, and thus to effect a measure of control over saponification in these respective 25 compartments insuring maintenance of saponification conditions as described above.

The saponification reaction mixture from the furthest downstream compartment 19 is passed directly to centrifugal 21, where it is separated 30 into soap and aqueous reagent phases, respectively, as described in the Scott patents mentioned above.

Figure 2 of the drawing illustrates a slight modification, by which a slightly different control of the extent of saponification in the respective mixing compartments is effected within the principles of the invention. As illustrated in that figure, fat, lye and brine from containers 30, 31 and 42, respectively, are passed by pumps 32, 33 and 43, respectively, to mixer 34, the fat being passed through a heater 35 if desired. The mixer 34 contains four mixing compartments, as illustrated, the first, third and fourth compartments, 36, 38 and 39 being smaller than the compartment 37. Compartments 37, 38 and 39 are provided with coils 40 for passage of a heat exchange fluid for heating and/or cooling as desired. A heating fluid is preferably passed through coil 40 of compartment 37, and application of relatively high heat in this compartment, together with the relatively large size of this compartment, insures saponification therein to an extent above 85%. The compartment 36 being smaller, and the degree of heat in this compartment being less, saponification may be controlled in compartment 36 to maintain it below 70%. Either heating or cooling fluid may be introduced into the coils of compartments 38 and 39, depending upon the degree of heat reached in compartment 37, it being important to provide a mixture for feed from compartment 39 to centrifugal 41 which will not flash into vapor upon introduction into that centrifugal. In the embodiment 65 of Figure 2, as in the embodiment of Figure 1, a separate quantity of fat is introduced into a compartment downstream from the compartment in which saponification in excess of 85% is first attained. As illustrated in Figure 2, a by-pass line 46 leads from a portion of line 47 connecting heater 35 with mixing compartment 36, and a part of the fat is conducted directly through the line 46 to mixing compartment 38. The relative proportions of fat fed to compartments 36 and 38, respectively, are controlled by 70 75

valves 45 and 44, respectively. It will be seen that, in this embodiment as well as in the embodiment of Figure 1, a degree of saponification in each of the respective compartments of the mixer can be maintained below 70% or above 85%, the embodiment of Figure 2 being practiced by maintaining it below 70% in compartment 38 and above 85% in compartments 37, 38 and 39.

The invention has been described above as though it involved the first stage of the saponification process. It may, however, be employed in the second or other subsequent stage of such a process. Thus, in practice of this invention in the second stage of a counter-current process, the fat-containing material fed from the container 10 or 30 is a mixture of fat and soap derived from the first stage of the process and containing a quantity of unsaponified available fatty acid (free and combined) in excess of 30%, due to maintenance of the precautions discussed above in practice of the first stage of the process to avoid saponification in excess of 70%. In such case, the process would be conducted in such a manner that the degree of saponification of the original saponifiable fat was raised to an extent above 85% in the compartment 16 or the compartment 37 (depending upon whether the invention was practiced in accordance with Figure 1 or Figure 2) and further fat would thereafter be added in a compartment subsequent to that in which saponification was first completed in excess of 85%, the other conditions of the invention also being maintained in the respective compartments as discussed above.

The features of the invention as discussed above may be employed either in a single stage process or in a multi-stage process, and the process being preferably a multi-stage counter-current operation. In the preferred practice of the invention, however, a continuous multi-stage counter-current process is employed as described in the above-mentioned Scott patents.

In this application, we are claiming the combination of features of control of the extent of saponification in the respective mixing compartments with the feature of addition of further fat in a compartment downstream from the compartment in which saponification in excess of 85% is first attained. In a co-pending application Serial No. 511,707, filed November 25, 1943, we are claiming broadly the feature of maintaining the reaction mixtures in the various mixer compartments in a suitable condition to avoid formation of difficultly inseparable emulsions.

The feature of heating the fat and later cooling the reaction mixture discussed in connec-

tion with Figure 1 is claimed in the patent to Scott, 2,348,855, of May 16, 1944.

Various modifications are possible within the scope of the invention, and we do not therefore wish to be limited except by the scope of the following claims.

We claim:

1. In the manufacture of soap by continuous saponification of fat, graining of the resulting soap and separation of grained soap from aqueous reagent solution by subsidence, the process comprising continuously passing a fat together with lye progressively through a succession of mixing compartments at a saponifying temperature, maintaining saponifying conditions in the respective compartments adapted to produce a saponified mixture in each compartment of which the proportion of the available fatty acid of the source of fat which has been saponified is outside of the range between 70% and 85% of said available fatty acid, said proportion of available fatty acid saponified in a compartment of the mixer at least one compartment upstream from the furthest downstream compartment being in excess of 85%, introducing a further quantity of fat into a compartment of said mixer downstream from the compartment in which said 85% of fatty acid saponification has first been attained, and controlling the saponification conditions in the compartment in which said further quantity of fat has been introduced and in any compartments of said mixer downstream from said compartment of introduction to produce a saponified mixture in each of said compartments of which the proportion of available fatty acid of the source of fat which has been saponified is above 85%, and subjecting the resulting mixture to centrifugation and thereby separating aqueous reagent from grained soap.
2. A process as defined in claim 1, in which saponifying conditions in each of the respective compartments are maintained to produce a saponified mixture in each compartment of which the proportion of the available fatty acid of the source of fat which has been saponified is above 85% of said available fatty acid.
3. A process as defined in claim 1, in which the saponification in the furthest upstream mixing compartment is below 70%, the saponification in a compartment downstream from said first-mentioned compartment is above 85% and the further quantity of fat is introduced in a compartment downstream from said last-mentioned compartment.
